UNITED STATES PATENT OFFICE.

JAMES BERNARD STEWARDSON, OF COLBY, KANSAS.

COUPLER.

Application filed April 16, 1925. Serial No. 23,599.

To all whom it may concern:

Be it known that I, JAMES BERNARD STEWARDSON, a citizen of the United States, and a resident of Colby, in the county of Thomas and State of Kansas, have invented 5 certain new and useful Improvements in Couplers, of which the following is a specification.

My invention relates to improvements in 10 couplers, and more particularly to a coupler of the type adapted particularly for use in coupling railway cars, and it consists in the combinations, constructions and arrangements herein described and claimed.

15 An object of the invention is the provision of a coupler of the character described which has a pivoted latch or coupling member that can swing to inactive or releasing position while the coupling is under the stress of the 20 usual load thereon without there being any necessity of first producing a slack in the coupling.

A further object of the present invention 25 is the provision in a coupler of a novel locking and operating mechanism for the pivoted latching or coupling member of the coupler, whereby the latching member normally will be held by gravity in active or latching position against the strain of the 30 load on the latching member, preventing the latching member from moving to open or releasing position until the locking and operating mechanism is manually operated to release. Also, when the latching member is 35 placed in open position, gravity will act on the locking and operating mechanism to hold it open, the locking and operating mechanism being so constructed as to be easily operated even when the strain of the 40 load is on the coupler.

A still further object of the invention is 45 the provision in a coupler of the character described of a draw head and a pivoted latching member having portions cooperating with each other to prevent abnormal movement of the latching member when the usual stress on the coupler is reversed, as when a car equipped with the coupler is being pushed.

50 A still further object of the invention is the provision of a coupler having provision made for the use of an emergency locking pin for holding the pivoted latching member of the coupler in latching position firmly, 55 although releasably, against the pull of the load, the emergency locking pin to be used

in case the locking mechanism is out of order.

Other objects and advantages of the invention will be apparent from the following 60 description, considered in conjunction with the accompanying drawings, in which:

Figure 1 is a fragmentary plan view of the improved coupler, portions thereof being broken away to disclose the underlying 65 structure,

Figure 2 is a section along the line 2—2 of Figure 1 looking in the direction of the arrows,

Figure 3 is a fragmentary side elevation 70 of a portion of the mechanism for operating the pivoted latching plate, and

Figure 4 is a perspective view of the emergency or auxiliary locking pin.

The improved coupling comprises a coupling member 1 having the outer end portion thereof enlarged at 2 and adapted to serve as a draw head. This draw head 2 is formed with a vertical slot 3 at its outer end, thus producing horizontally spaced furcations 4 and 5, respectively. The slot 3 enlarges toward its outer end to provide a flaring mouth into which any suitable coupling knuckle that is carried by a cooperative coupler member, not shown, may move 80 when the cooperative coupler members are moved together. The draw head 2 also has a horizontal slot 6 which extends laterally in the draw head through the furcation 5. A latching or coupling member operable to 85 releasably retain the aforesaid coupling knuckle of the cooperating coupler member in the slot 3 has substantially the shape of a bell crank lever and is fulcrumed on a vertical pivot element 7 which extends 90 through the slot 6 between the vertically spaced portions of the furcation 5 adjacent to the outer end of the latter. This pivoted latching member comprises a knuckle portion 8 which is movable horizontally to and 95 from position to extend in the mouth of the slot 3 part way across the latter, and to then prevent the aforesaid coupling knuckle from disengaging the draw head. The pivoted latching member also includes a knuckle operating arm 9 which is movable horizontally 100 in the slot 6 as required, to move the knuckle 8 between active latching position and inactive releasing position. The knuckle operating arm 9 is provided with an extension 10 at its inner edge for engaging with an outwardly facing stop shoulder 11 on the inner

105 110

wall of the slot 3 for the purpose of limiting the swinging movement of the knuckle 8 across the mouth of the slot 3 without causing any stress on the mechanism that the invention provides for operating the latching member, this feature being particularly important when the knuckle operating arm of the latching member is under stress resulting from the pushing of the car to which the 10 coupler member 1 is attached, as a result of force imparted to the car through the coupler.

The operating arm 9 has an integral laterally extending ear 12 having a vertical opening 13 formed therein. A rigid link 14 has an eye 15 at its inner end engaged with the opening 13. An arm 16 extends laterally from the draw head 2 at the inner end of the slot 6. The arm 16 preferably is integral 20 with the draw head. A second arm, indicated at 17, is formed separately from the draw-head, and has a flanged inner end portion 18 bolted at 19 to a flanged laterally extending portion 20 of the draw head so that 25 the arm 17 will be disposed in spaced parallel relation to the arm 16 and the link 14 will be disposed between the arms 16 and 17. The horizontal slot 6 extends in the laterally extending portion 20 of the draw head so 30 that space is provided for movement of the ear 12 in a horizontal plane when the knuckle operating arm 9 moves in the slot 6 in the manner hereinbefore described. The arms 16 and 17 are provided with aligned 35 transverse openings 21 in which are journaled trunnions 22 which extend from opposite sides of the inner end portion of a channel shaped link actuating arm 23 which thus is pivotally supported to swing in a vertical plane between the arms 16 and 17.

The purpose of making the arm 17 separate from the draw head is to permit the arm 23 to be placed between the arms 16 and 17 and to be swingingly supported on the arms 45 16 and 17 in the manner described. The bottom or web portion of the channel member 23 is indicated at 24, and is best seen in Figure 2.

The rigid link 14 is formed with an eye 50 25 at its outer end. A pin 26 extends across the channel of the member 23 intermediate the length of the latter, and through the eye 25, thus pivotally attaching the link 14 to the member 23. A pin 27 extends across 55 the channel of the member 23 adjacent to the outer end of the latter, and carries a roller 28. The bottom or web 24 of the member 23 is cut away at its outer edges as indicated at 29 so that the roller 28 depends below the 60 plane of the bottom 24, and has the periphery thereof in contact with a cam 30 on a cam shaft 31 which is journaled in aligned openings in the arms 16 and 17 adjacent to the outer ends and to the lower edges of the 65 latter.

The pins 26, 27 and 31 are parallel with one another and with the axis of swinging movement of the member 23. The axis of swinging movement of the member 23 is located at a level which is higher than the 70 centers of the eyes 15 and 25 when the link 14 and the latching member of the coupler are in the positions shown in Figure 1 and in full lines in Figure 2. Therefore, the member 23 normally is past center and the 75 latching member of the coupler normally is urged by gravity to active latching position.

A rocker arm 32 is carried by an extending end portion of the rock shaft 31 and is connected by a chain 33 to the outer end of a 80 lateral arm 34 which is secured on an extending end portion of one of the trunnions 22.

From the foregoing description of the various parts of the device, the operation 85 thereof may be readily understood. When it is desired to move the latching member of the coupling to releasing position, a lever 35 which is connected at its lower end to the cam shaft 31 is manipulated to rock the 90 cam shaft 31 in a clockwise direction. This causes turning of the cam 30 from the position shown in full lines in Figure 2 to position to raise the outer end of the member 23 to the extent required to position the axis 95 of the pivot pin 26 and therefore the center line of the eye at the outer end of the link 14 above the level of the axis of swinging movement of the member 23. At this position, the coupler is unlocked and the pull on the 100 knuckle will cause the parts to move to open position. At the time the outer end of the member 23 reaches the position just described, the slack in the chain 33 will have been taken up by reason of the swinging of 105 the arm 32 away from the arm 34 and continued manipulation of the lever 35 to rock the shaft 31 further in a clockwise direction will cause continued upward movement of the outer end of the member 23 and of the 110 outer end of the link 14, whereby the knuckle actuating arm 9 of the latching member will be shoved inward in the horizontal slot 6 and the knuckle 8 will be moved to releasing position. When in the open position, the 115 weight of the member 23 will cause parts to remain in this position.

It may be desirable in an emergency to lock the latching member of the draw head in the latching position so that the pull of 120 the load will be ineffective to swing the latching member to releasing position. To this end, the invention provides a vertical opening 35' in the draw head at the inner end of the slot 3 and at the outer side of the extension 10 of the knuckle actuating arm 9. A headed coupling pin 36 may be placed in the vertical opening 35' and will engage with the outer side of the extension 10 of the latching member to hold the latter against 125 130

the shoulder 11, whereby the latching member will be substantially rigid with the draw head so long as the coupling pin 36 is in place.

5 Obviously, the invention is susceptible of embodiment in forms other than that which is illustrated in the accompanying drawings, and I therefore consider as my own all such modifications and adaptations thereof as 10 fairly fall within the scope of the appended claims.

I claim:

1. In a coupler, a draw head having a vertical slot and having a horizontal slot, 15 a latching member fulcrumed in the horizontal slot to swing to and from position to project to latching position in said vertical slot, a vertically swingable toggle mechanism attached at one end to said latching member, said toggle mechanism being actuated by gravity to urge said latching member continuously to latching position, and means for actuating said toggle mechanism to move said latching member to 20 releasing position.

2. In a coupler, a draw head having a vertical slot and having a horizontal slot, a latching member fulcrumed in the horizontal slot to swing to and from position to 25 project to latching position in said vertical slot, a vertically swingable toggle mechanism attached at one end to said latching member, said toggle mechanism being actuated by gravity to urge said latching member continuously to latching position, a cam 30 for raising the lower end portion of said toggle mechanism above center position, and other means for actuating said toggle mechanism to move said latching member to 35 releasing position.

3. In a coupler, a draw head having a vertical slot for the reception of a coupling link, said draw head also having a horizontal slot extending from one side of the draw 40 head to said vertical slot, a vertical pivot element extending through the outer end of said horizontal slot, a latching member fulcrumed on said pivot element and having a knuckle portion movable to and from position to extend to latching position in the 45 mouth of said vertical slot, said latching member including a knuckle actuating arm, movable in said horizontal slot, said draw head having a pair of spaced supporting 50 arms extending laterally therefrom, a link rigidly attached at its inner end to said knuckle actuating member, a link actuating member supported at its inner end between 55 said laterally extending supporting arms

for swinging movement about a horizontal axis, means pivotally connecting the outer end of said link to said link actuating member, the axis of swinging movement of said link actuating member being located above the level of the center lines of the point of 60 connection of said link with said link actuating member, whereby said link will be actuated by gravity to hold said latching member in latching position, means for raising the outer end portion of said link actuating member to position to cause swinging of said latching member to releasing position.

4. A coupling comprising a draw head, 65 a pivoted knuckle carried by the draw head, a knuckle actuating arm rigid with the knuckle, a pair of laterally extending spaced supporting arms carried by the draw head, a channel member having trunnions at its inner end journaled in said supporting arms, 70 a straight rigid link having its outer end pivotally supported between the arms of said channel member and its inner end pivotally attached to said knuckle actuating arm, and means for operating said channel member 75 to transmit motion through said link to said knuckle actuating arm.

5. A coupling comprising a draw head, 80 a pivoted knuckle carried by the draw head, a knuckle actuating arm rigid with the knuckle, a pair of laterally extending spaced supporting arms carried by the draw head, a channel member having trunnions at its inner end journaled in said supporting arms, 85 a straight rigid link having its outer end pivotally supported between the arms of said channel member and its inner end pivotally attached to said knuckle actuating arm, the axis of swinging movement of said channel member being above the axis of the 90 pivotal connection of the outer end of the link with the channel member when said channel member is substantially horizontal, a roller at the outer end of the channel member, a cam shaft below said roller having a 95 cam on which said roller rests, a rocker arm rigid with the cam shaft, a rocker arm rigid with one of said trunnions, a flexible connection between said rocker arms, and means 100 for rocking the cam shaft, said flexible connection being slack until the pivotal connection at the outer end of the link has been raised with said channel member by said cam above the level of the center lines of 105 said trunnions and then being taut, as and 110 for the purpose described.

JAMES BERNARD STEWARDSON.
